UNITED STATES PATENT OFFICE.

JOHN ROSCOE MILLWARD, OF TENAFLY, NEW JERSEY.

RAIL JOINT.

Application filed January 7, 1922. Serial No. 527,640.

To all whom it may concern:

Be it known that I, JOHN ROSCOE MILLWARD, a citizen of the United States, residing at Tenafly, in the county of Bergen and 5 State of New Jersey, have invented new and useful Improvements in Rail Joints, of which the following is a specification.

This invention relates to rail joints and consists of an improved welded joint structure and method of weldingly securing the splice bars in a rail joint designed to possess substantial advantages over the welded types of joints as heretofore produced.

An important object accomplished by my 15 present invention is the production of a welded joint which will successfully permit of the relative movement of the meeting rail ends in expanding and contracting under changes of temperature. My improved joint 20 structure is thereby adapted for successfully securing the exposed type of rail installations in a more rigid and permanent manner than at present employed with valuable 25 advantages and economy. A further feature of importance resides in an improved manner of weldingly securing the joint with the minimum of welding to the rail and by confining the welding connection to the rail so as to reduce the danger of impairing the 30 strength of the rail to a negligible degree. In the preferred embodiment of my invention my improved joint performs the additional function of anchoring the rail thereby eliminating the necessity of anti-creeping 35 devices or reducing the number employed for that purpose.

The aforesaid and other features and advantages of my invention will be understood 40 by reference to the accompanying drawings wherein like reference characters are employed to denote the corresponding parts in the several views.

In the drawings:

Fig. 1 is a plan view showing a rail joint 45 embodying the features of my invention.

Fig. 2 is a perspective view thereof.

Fig. 3 is a cross-sectional view thereof on line 3—3 of Fig. 1.

Fig. 4 is a similar view on line 4—4 of 50 Fig. 1.

In the approved embodiment of my invention, as illustrated, 1 and 2 indicate the aligned or meeting rail ends to the joined, 3—3 the oppositely positioned splice bars and 55 4 the base plate secured to the ties 5—5 by the usual spikes 6. The splice bars are

shown of the angle bar type with their base flanges 7 having their lower edges or surfaces in close proximity to the upper surface of the base or joint plate 4. The base or tie plate 4 is of a standard joint plate construction arranged to bridge the ties and having flat rail bearing surfaces at each end with its intermediate side portions deformed to provide depending reinforcing flanges 8 at each 65 side between the ties and is provided at its ends with the upturned rail aligning lugs 10—10.

In accordance with my invention the splice bars are secured in position by welding 70 to produce a joint having advantages of permanency of installation and in an improved manner permit of the required relative movement of the rail ends thereby to successfully meet the conditions imposed in exposed rail 75 installations. In its simplest expression my invention contemplates weldingly securing each of the splice bars to one rail end only thereby to allow longitudinal movement of the other rail relative thereto. In the preferred arrangement this is accomplished to embody the additional improved features 80 providing for rigidly securing the splice bars by welding connection to the under side of the rail heads only so as to conserve to the maximum degree the strength of the rail.

In the preferred arrangement illustrated in Figs. 1 to 3 each of the splice bars is welded along its uppermost edge at a—a to the underside of the head of one rail end, the rail 2 as illustrated. The base flanges of the splice bars are similarly secured by wells b—b at their lower outer edges to the upper surface of the base or joint plate at the flattened bearing ends thereof. As will be noted 90 the resulting connected structure provides for rigidly securing of the splice bars so as to leave one rail end, the rail end 1 as indicated, free to move longitudinally under expansion and contraction relative to each of the splice bars. In practice and as shown the splice bars may be additionally secured at each end by the usual connecting bolt 12 which may advantageously be employed to initially hold the bars in position during 95 the welding operation. The latter may be effected by any suitable welding flame.

As will be understood in a continuous rail each joint will be similarly constructed whereby one end only of each rail section will be rigidly secured to the splice-bars and base plate.

The described arrangement provides for rigidly and firmly securing the joint in a permanent manner with welding connection between the splice bar and the rail at one end only and with the weld positioned between the lower edge of the rail head and the head or top surface of the bar. The welding connection to the rail is thus restricted to the portion thereof wherein the substantial strains are compressive, my improved arrangement being designed particularly to avoid welding to the lower portion or base of the rail where the weld would be detrimental to the strength of the rail in its effect on the physical structure of the steel. The location of the weld connecting the splice-bars to the base plate is also such as to impair the strength of the bar to a negligible degree if at all.

A further valuable advantage of my improved joint obtains by reason of the rigid connection between the rail and the base plate. As a result the rail is securely anchored against longitudinal creeping movement, the opposition to this movement being advantageously distributed between the two ties connected to the joint or base plate which jointly operate to oppose movement.

While I have described and shown an approved embodiment of the features of my invention it will be understood that they are subject to various modification and application without departing from the scope of the invention as defined in the appended claims. For instance while I have shown in the disclosure a single base or joint plate bridging two ties, separate tie plates may be used upon the respective ties in the customary manner or the base plate may be extended over more than two of the ties to increase the anchoring effect.

As illustrated, the length of the weld connecting the top of the splice bar to the under-side of the rail head may desirably be proportioned whereby the weld does not extend to the extreme end of the splice bar whereby such weakening of the physical structure of the steel, as may occur by reason of the welding operation, will be limited to that portion of the rail which is fully reinforced by the splice bars. Also as will be further understood the welding connection of the rail head may be desirably proportioned with relation to the bonding effect to permit of the dismantling of the joint structure by the driving in of a wedge between the splice bar and rail to facilitate the operation of replacing track.

Having described my invention I claim:

1. A rail joint structure comprising the rails, oppositely positioned splice bars arranged to connect the rail ends and a joint plate positioned thereunder, each of the splice bars being connected by welding to

one rail end and to the underside of the head 65 only and connected at its lower edge to the plate and said plate being secured to a plurality of ties, substantially as described.

2. A rail joint structure comprising the rails, oppositely positioned splice bars connecting the rail ends and a base plate underlying a portion of the splice bars, each of the splice bars being connected to one rail end only and to the base plate by a welding operation.

3. A rail joint structure comprising the rail, oppositely positioned splice bars connecting the rail ends and a base or joint plate positioned to underly a portion of the splice bars, each of the splice bars being connected to one rail end only and to the underside of the head thereof by welding and having its lower flange portion secured by a welding connection to the plate, substantially as described.

4. The herein described method of securing rail joint structures comprising the rails, base plate and splice bars for connecting the rail ends consisting in weldingly securing each of the splice bars to one rail end only and to the base plate, substantially as described.

5. The herein described method of securing rail joint structures comprising the rails, base or joint plate and splice bars for connecting the rail ends, consisting in weldingly securing each of the splice bars at its upper edge to the underside of one rail head only and weldingly securing each of the splice bars at its lower edge to the base plate, substantially as described.

6. In a rail joint structure comprising the rails, oppositely positioned splice bars connecting the rail ends and a base plate underlying the splice bars, means for securing the splice bars comprising a connecting weld between the splice bar and the base plate.

7. A rail joint structure comprising the rails, oppositely positioned splice bars connecting the rail ends and a base plate underlying a portion of the splice bars, each of the splice bars being connected to one rail end only and for substantially their full length to the base plate by a welding operation.

8. A rail joint structure comprising the rails, oppositely positioned splice bars of standard angle bar section arranged to connect the rail ends and a joint plate positioned thereunder, each of the splice bars being connected by welding to one and the same rail end and to the underside of the head only and at its lower edge to the plate for substantially its full length.

In testimony whereof I have signed my name to this specification.

JOHN ROSCOE MILLWARD.
